Benton P. Coster. 439

The Schedule referred to in the Letter Patent and (including) part of the same containing a description in the words of the said (Benton P. Coster) himself of his "invention
consisting in certain parts of the process of bleaching wool,
renovating feathers."

To all to whom these presents shall come
Be it known that I Benton P. Coster of Herting
in the County of Niagara and State of Pennsylvania
have invented new and useful improvements in cer-
tain parts of the process of renovating or bleaching feathers
and that the manner in which the same is to be per-
formed, is particularly described and set forth in
the following application and description hereof
and of one of the modes in which the same may be em-
ployed with effect, reference being had to the drawings here-
unto annexed (and to the letter marked therein, that
is to say). The application of steam within the cylinder that forms
an enclosure for the feathers during the process of bleaching
made by means of a tube or hollow exploding through the
ends of it, and which is made to revolve thereby for the
purpose of agitating them has been already known and used,
and therefore forms no part of my invention, though
this method of using the steam (may) serve for the first
part of the operation; but after that is done I take care
first and so as to force it amongst the feathers in all direc-
tions in the same manner. I also discharge the feathers
from the cylinder after they are finished by means of
forcing them at one end of it through an opening made
in the pipe, so as to drive them out at a doorway
made large enough to admit of their free passage out.
But in order that my invention may be better understood I will
more particularly describe the bleaching process annexed, by the latter there

is the manner been during the first part of the operation, by which means they will
be thoroughly dried, after the action of said steaming.

476

on marked, that is to say, Fig. 1. is an elevation of the machine showing the construction of a hollow shaft and means to revolve by means of a pulley. A. serving to disperse the hot air amongst the feathers, the whole revolving within a cylinder. A. shaped either as a dodecahedron or other similar figure. This cylinder is left open along the sides at intervals, say, one-third spaces, upon the lower half only, as will be described hereafter. These spaces are left covered by means of loose work, or gratings, so as that the heat & impurities arising in them by the rush of air through the eye is sent across hatching out at these openings made of cuttings, as at B. At one end is made the opening or door C. through which the feathers when finished are drawn out by the form of the letters D. acting above the receiver or hot air chamber E. and forcing the air through the tube F. by the opening G. so as to produce a current directed thereby through the hatching C. so that all the feathers are discharged at once. Considered that the stop cock H. had been previously opened for that purpose, whether tube I. leads from the air chamber so as to be introduced into the mouth of the hollow pipe J. which is also to be furnished with the stop cock K. & R. which being opened will使 that of I. be closed, allows the hot air to escape into the hollow pipe J. & thence be distributed by means of the arms L. through the feathers in such manner as have previously been shown, by the introduction of another tube with stop cock K. which is to conduct the steam from old chamber as has been already need and known used for which reason I do not now consider this here, though I prefer introducing steam through a separate tube to make it into the cylinder, but the shaft is not all connected with it. The application of heat is of course made below the air chamber into which the air is compressed or forced by any

of the known modes in use. The ordinary tube bellows being one well adapted to the purpose and this is applied at the top of the tube *N* leading into the receiver. To *N* the cock *R*, valve *H*, being closed the chamber may be filled and the heating ready for application. When the cock *R* being opened the contents may be forced by the use of the bellows *B* through the tube *T* into the bellows *A* at *J*. The cylinder *C* is to be enclosed in an outside case as shown at *O* which will reach about half way up the side of said cylinder so as to inclose the gratings *B* as above described. There is also to be a door for the introduction of the feathers at the top of the cylinder as at *P*. It will also appear that the dust and impurities driven off through the gratings *B* must be of course received within the case *O* at the ends of which is made the draft opening or flue *Q* for the purpose of carrying off ^{it all} as well as the steam & c which would otherwise become annoyance in the work room. The hollow shaft, as well as the arms are furnished with small apertures ^{numerous} dispersed throughout for the purpose of distributing the hot air. In the operation according to my process, I first make use of steam inserted through the separate tube as described until the feathers are clean, when by shutting it off by the cock *M* and opening those at *K* & *R*, the force of the bellows is applied at the top of the tube *N* when the heating air is driven through the tube *T* & *C* until the feathers are completely dried by the agitation. When closing the cock *K* & opening *R* the cold air is drawn by the tube *E* through the opening *G*, so as to displace the feathers through the door *C*, the gratings *B* being previously closed by shutters on sliding doors. When the said feathers fall into the situation described perfectly dry and dry. What I claim as my invention and for which I wish Letters

Galters Patent is the improvement in the process of an
oating feather by introducing hot air to dry them (and blow
off the impurities after they have been cleaned by steam in
the ordinary way, according to the above description
thereof. Also for cooling and drying them by the
forcing in of cold air as explained; & for excepting
any part that might be unwholesome, apparatus substantially
the same as that hereinbefore mentioned and set forth.

In testifying to the above, to a full description
I have herewith set down:
